UNITED STATES PATENT OFFICE.

JAMES S. THOMPSON, OF PELHAM, NEW YORK.

BRAKE-SHOE MOLD.

Application filed July 20, 1923. Serial No. 652,775.

To all whom it may concern:

Be it known that I, JAMES S. THOMPSON, a citizen of the United States, residing at Pelham, in the county of Westchester and State of New York, have invented certain new and useful Improvements in Brake-shoe Molds, of which the following is a specification.

This invention relates to the manufacture of brake shoes, and more particularly to the mold in which the shoe is cast, and its object is broadly to enable a brake shoe to be cast in a permanent mold fully as well as it can be cast in a sand mold and with the additional advantages of reduction in time and labor.

A further object of the invention is to provide a mold which can be easily and quickly opened and closed to permit insertion of any parts which are to be embedded in the shoe casting, and to permit removal of the shoe.

And a further object of the invention is to make the cope of the mold in two members, hinged to swing oppositely and each having a portion of the mold cavity therein, with means for supporting parts to be inserted in the shoe casting in that portion of the mold cavity which is located in one cope member so that the other cope member may be closed without injuring or disarranging said parts.

My invention also has other objects in view which will be pointed out hereafter in the detailed description thereof by reference to the accompanying drawings, which show a selected embodiment of the invention, and referring to which—

Fig. 1 is a transverse sectional view on the line 1—1 of Fig. 2.

Fig. 2 is a longitudinal view partly in elevation and partly in section.

Fig. 3 is a horizontal sectional view on the line 3—3 of Fig. 2.

Fig. 4 is a perspective view showing a portion of the drag in section and a portion of one member of the cope in elevation.

Fig. 5 is a fragmentary view partly in section of the refractory material which forms the mold cavity wall in one member of the cope.

Fig. 6 is a detail perspective view of the core for forming the opening in the attaching lug.

Referring to the drawings, the mold com-

prises a drag member 7 and two cope members 8 and 9 having a mold cavity 10 therein. The drag member is relatively fixed and is provided with outstanding side lugs 11 with which the outstanding side lugs 12 on the cope members are pivotally engaged by the pivot bars 13. The mold cavity is formed partly in one cope member and partly in the other cope member, the parting line between said members extending longitudinally of the mold and substantially central of the mold cavity. This construction provides a simple means for opening and closing the mold and it also enables the parts to be embedded in the shoe casting to be arranged in the mold and held therein securely for proper positioning in the shoe casting. It is important also to make provision for closing the cope members without injury to and without disarranging the parts to be embedded in the shoe casting, and also to enable the cope members to be opened for the removal of the shoe casting without damage to any parts of the mold.

I have accomplished these desirable results in a very simple manner in this invention whereby brake shoes can be made in permanent molds as well as they can be made in sand molds, and even with greater perfection, and at a greater speed and less cost.

It is customary to embed a steel attaching lug 14 and a steel reinforcing back 15 in the shoe casting, and it is also customary to provide a sand core 16 for forming the opening in the attaching lug. A recess 17 in the two members of the cope forms a part of the mold cavity and accommodates the attaching lug 14 and the sand core 16, and since this sand core and attaching lug will be supported partly in one cope member and partly in the other, it will be necessary to construct the walls of the recess and the sand core in such a manner that the cope members can be closed without damage to the core. I preferably construct that part of the recess in one core member and that part of the core which fits therein in a manner to hold and support the core while the members are being closed, and during the casting operation, and I make that part of the recess in the other core member and the corresponding part of the core so that said other core member can be opened or closed after its companion

core member has been closed and without damage to the core or disarranging any of the parts associated therewith. I will refer for convenience to the core member 8 as the 5 left member and to the core member 9 as the right member and describe the construction thereof as shown in the drawings, it being understood that these parts may be reversed if found desirable. The left core member 8 has its half of the recess 7 provided with end extensions 18 having inclined end walls 19, Fig. 4, to receive the extensions 20 having inclined faces 21 at the ends of the core, 16, Fig. 6. It will be noted that 10 these extensions 20 are located at the top and on one side only of the core and they may be said to represent, for purposes of description, one upper corner of each end of the core. The reinforcing back is prefer- 15 ably fastened to the core by wire ties 22, and when the attaching lug, the core and the reinforcing back are assembled as a unit, they can be easily inserted sidewise into that part of the mold cavity in the left 20 core member 8 when the latter is in open position, as shown in broken lines in Fig. 1, after which this left core member can be 25 swung to closed position without dislodging or disarranging said unit, and then the right 30 core member 9 can be closed without dislodging or disarranging said unit, which is then positioned and held in the cavity to be properly embedded in the shoe casting. In order that the right core member 9 may 35 be closed without injury to the core 16, I prefer to make the upper part 23 of each end wall in that part of the recess formed therein inclined reversely to the adjacent inclined end wall 19 on the left member, 40 and also to reversely incline the adjacent upper quarter 24 of the end of the core to the inclination of the adjacent quarter 21, so that the effect is to cut away the upper corners of that portion of the core which 45 enters that portion of the recess located in the right cope member. The core is made to fit in the recess in the left cope member, and the recess in the right cope member is made to fit on that portion of the core with which 50 it engages, and the construction is such that the core may be inserted in the left cope member 8 when the latter is in open position, and this left cope member can then be closed without dislodging or disarranging 55 the core, after which the right cope member 9 may be closed without damaging or disarranging the core. This is an important feature of my invention because it enables the mold to be loaded, so to speak, 60 and prepared for the casting operation, and also enables the casting operation to be performed, without in any way damaging or disarranging the load, so that the parts to be embedded in the shoe will be properly 65 disposed and embedded therein, and it also

enables the mold to be opened easily and the casting removed without damage to any part of the mold.

My invention can be embodied in a mold in which the mold cavity is faced with refractory material 25 throughout to prevent the metal of the mold members from chilling the casting, as shown in the drawings, or the refractory material may be applied in sections in any desired manner to permit 75 the shoe casting to be chilled at certain parts. My invention provides a mold of simple, compact, convenient and substantial construction which can be easily and quickly operated for the production of a brake shoe. 80 When the cope members are thrown to open position for removal of the shoe casting, they are at the same time positioned for the reception of the parts to be embedded in the casting, and this can be easily done and 85 the mold closed again without the exercise of special skill or any considerable amount of labor. I provide one or more clamps 26 for holding the two members of the cope in closed position, and this also holds the 90 two members rigid with the drag member. I also provide one or more sand plugs 27 in the cope to permit the escape of gases from the mold cavity.

My invention can be employed for making castings other than brake shoes, and I consider myself entitled to make all such changes in the form, construction and arrangement of parts as may be necessary or desirable for this purpose, and for making 100 different kinds, shapes and sizes of brake shoes, which fairly fall within the scope of the following claims.

I claim—

1. A permanent mold for making castings, comprising a drag and a two-member cope having a mold cavity therein, said cope members being hinged on the drag member to swing outwardly thereon, each of said cope members having a part of the mold cavity therein and adapted to accommodate a portion of the parts which are to be embedded in the casting, and means for holding said parts in one cope member and for permitting the other cope member to be 110 swung to closed position without disarranging said parts.

2. A permanent mold for making castings, comprising a drag and a two-member cope having a mold cavity therein, said cope members being hinged on the drag member to swing outwardly thereon, each of said cope members having a part of the mold cavity therein and adapted to accommodate a portion of the parts which are to be embedded in the casting, said cope member being adapted to receive said parts while it is in open position, and means for holding said parts in said cope member while it is being swung from open to closed position 120

and while the other cope member is being closed.

3. A permanent mold for making castings, comprising a drag and a two-member cope having a mold cavity therein, said cope members being hinged on the drag member to swing outwardly thereon, each of said cope members having a part of the mold cavity therein and adapted to accommodate a portion of the parts which are to be embedded in the casting, and means in one cope member for holding said parts therein while the mold is being closed and during the casting operation.

4. A permanent mold for casting a brake shoe, comprising a drag and a two-member cope having a mold cavity therein, said cope members being hinged on the drag member to swing outwardly thereon, each of said cope members having substantially a longitudinal one half of the mold cavity therein and adapted to accommodate a corresponding portion of the parts which are to be embedded in the shoe casting and including the core for forming the opening in the attaching lug, and means for holding said parts in one cope member during the closing of the mold and during the casting operation and for permitting the other cope member to be freely opened and closed without affecting said parts.

5. A permanent mold for casting a brake shoe, comprising a drag member and a two-member cope having a mold cavity therein, said cope members being hinged on the drag member to swing outwardly thereon, each of said cope members having substantially a longitudinal one half of the mold cavity therein and adapted to accommodate a corresponding portion of the parts which are to be embedded in the shoe casting and including the core for forming the opening in the attaching lug, and means cooperating with said core to hold and support said parts in one cope member while the mold is being closed and during the casting operation and without interfering with the closing or opening of the other cope member.

6. A permanent mold for casting a brake shoe, comprising a drag and a two-member cope having a mold cavity therein, said cope members being hinged on the drag member to swing outwardly thereon, each of said cope members having a part of the mold cavity therein and adapted to accommodate a corresponding portion of the parts which are to be embedded in the shoe casting and including the core for forming the opening in the attaching lug, and shoulders in the walls of that portion of the cavity in one cope member to cooperate with shoulders on said core for holding and supporting said parts in said cope member while the mold is being closed and during the casting operation.

7. The combination with a core for forming the opening in the attaching lug of a brake shoe and having an extension thereon, of a permanent mold for casting the brake shoe and comprising a drag and a two-member cope having a mold cavity therein, said cope members being hinged on the drag member to swing outwardly thereon, each of said cope members having a part of the mold cavity therein and adapted to accommodate a portion of said core and one of said members having that part of the mold cavity therein formed to accommodate the extension on the core, substantially as and for the purpose described.

8. The combination with a core for forming the opening in the attaching lug of a brake shoe and having a corner extension thereon, of a permanent mold for casting the brake shoe and comprising a drag and a two-member cope having a mold cavity therein, said cope members being hinged on the drag member to swing outwardly thereon, each of said cope members having a part of the mold cavity therein and adapted to accommodate a portion of said core and one of said members having that portion of the mold cavity therein formed to accommodate the corner extension on the core, substantially as and for the purpose described.

9. The combination with a core for forming the attaching lug in a brake shoe and having corner extensions at its ends, of a permanent mold for casting the brake shoe and comprising a drag and a two-member cope having a mold cavity therein, said cope members being hinged on the drag member to swing outwardly thereon, each of said cope members having a part of the mold cavity therein and adapted to accommodate a portion of said core and one of said members having that part of the mold cavity therein provided with extensions to accommodate the corner extensions on the ends of the core, substantially as and for the purpose described.

10. The combination with a core for forming the opening in the attaching lug of a brake shoe and having corner extensions thereon with inclined faces, of a permanent mold for casting the brake shoe and comprising a drag and a two-member cope having a mold cavity therein, said cope members being hinged on the drag member to swing outwardly thereon, each of said cope members having a part of the mold cavity therein and adapted to accommodate a portion of said core and one of said members having that part of the mold cavity therein formed with extensions and inclined walls to accommodate the extensions on the core, substantially as and for the purpose described.

11. The combination with a core for forming the opening in the attaching lug of a

brake shoe and having corner end extensions thereon with inclined faces, adjacent corners at the top of the core being reversely inclined, of a permanent mold for casting the 6 brake shoe and comprising a drag and a two-member cope having a mold cavity therein, said cope members being hinged on the drag member to swing outwardly thereon, each of said cope members having a part 10 of the mold cavity therein shaped to fit that

part of the core which is seated therein, substantially as and for the purpose described.

12. A core for forming the opening in the attaching lug in the manufacture of a brake 15 shoe, and having at each end one upper corner extended and provided with an inclined face and its other upper corner reversely inclined.

JAMES S. THOMPSON.
